United States Patent Office

Des. 179,011
Patented Oct. 23, 1956

179,011

PLATE

Raymond T. Kimble, Cambridge, Ohio, assignor to The Cambridge Glass Company, Cambridge, Ohio, a corporation of Ohio

Application April 4, 1956, Serial No. 40,920

Term of patent 14 years

(Cl. D36—2)

FIG. 1

I claim:

The ornamental design for a plate, substantially as shown.
